UNITED STATES PATENT OFFICE.

WILLIAM B. CUTHBERTSON, OF NEW BRIGHTON, PENNSYLVANIA.

ROTARY EXPLOSIVE-ENGINE.

SPECIFICATION forming part of Letters Patent No. 677,949, dated July 9, 1901.

Application filed June 6, 1900. Serial No. 19,810. (No model.)

To all whom it may concern:

Be it known that I, WILLIAM B. CUTHBERTSON, a citizen of the United States, residing at New Brighton, Beaver county, State of Pennsylvania, have invented certain new and useful Improvements in Motors, of which the following is a specification.

My invention relates to motors; and it consists in means whereby to secure a practically continuous motor fluid-pressure; and to this end my invention consists in the combination, with a motor, of a casing having a pressure-chamber in which pressure is created and maintained by the explosion of a succession of charges of explosive mixture, as fully set forth hereinafter and as illustrated in the accompanying drawings, in which—

Figure 1 is a sectional elevation on line xx with the casing removed and on line zz of Fig. 2 of an apparatus embodying my improvement; Fig. 2, a transverse sectional plan; Fig. 3, an edge view, and Fig. 4 a section illustrating a modification.

The casing A is of any suitable character and is mounted upon a suitable base and contains a pressure-chamber N, which communicates with a suitable motor G. This motor may be any suitable turbine; but, as shown, it is a turbine having a member with fixed blades and a rotative member carrying other blades, as in ordinary turbines, the rotative member being mounted upon a shaft C, turning in suitable bearings of the casing.

Within the pressure-chamber N is arranged a series of barrels D, open at the opposite ends, and preferably each barrel is surrounded by a water-jacket W, Fig. 4, as shown. Water is maintained in circulation through these jackets in order to prevent the overheating of the barrels.

A disk B, which rotates with its inclined periphery in as close proximity as possible to an annular inclined face of the casing A, constitutes a breech for the barrels D, closing the outer ends of the latter. The inner ends of the barrels are closed by a disk F, and in this disk F are openings M, which are brought opposite the inner ends of the barrels at the moment when the charge in the latter is exploded.

Any suitable means is provided whereby the barrels are supplied (in succession, preferably) with an explosive mixture and whereby the explosive mixture after being introduced is exploded, the result of the explosions (preferably in rapid succession) being to fill the chamber N with a gas or mixture of gases under pressure, which flows to the motor and puts the latter in operation.

One means of supplying the barrels in succession with the explosive mixture consists in providing a port J in the casing A, adjacent to each barrel, and forming in the disk B a channel j , so arranged as to be brought opposite the outer end of a barrel D and simultaneously opposite a port J in the casing A, which port communicates with a pipe leading to a supply of gaseous mixture under pressure. By this arrangement as the channel j is brought opposite a barrel D and a port J the gaseous mixture under pressure will flow from that port J through the channel j and into the barrel D. The end of the channel j opposite the barrel D is elongated or curved, so as to remain in communication with the barrel during the rotation of the disk B until the barrel is filled, when the passage of the channel opposite the port J will cut off the supply and bring the flat face of the disk B opposite the end of the barrel D. In the disk B, following the channel j , is another channel h , also having an elongated inner end and which as it is brought opposite the barrel D is also brought into communication with an outlet-port H, there being an outlet-port for each barrel, so that after the explosion of the barrel D the products of combustion, if any, which have not escaped into the chamber N may have a free access to the channel h and port H. Each opening M in the ring or disk F is so arranged that it is brought opposite the inner end of a barrel D, and the charge in the latter is exploded, so that the gases flowing from the barrel will pass directly to the chamber N. The explosion of the charge in the barrel D is then followed by the closing of the latter by the plane portion of the disk or ring F.

Any suitable means may be employed for igniting the charge in the barrel D. For in-

stance, in the plane portion of the breech-disk B between the channels; and *h* is an opening *y*, and outside of the disk B is mounted a flame-igniter K on the disk in such position 5 that as the opening *y* is brought opposite the barrel the gas passing through the opening will be projected against the flame and ignited, and the charge in the barrel will be exploded just as the opening *y* passes beyond 10 the barrel.

I have illustrated the flame-igniter as one means only whereby the explosion may be effected; but an electrical igniter or any other means of igniting the charge may be employed. 15

I have described the operations only in connection with one of the barrels; but the same operation takes place for each barrel in turn, and it will also be evident that any suitable 20 number of barrels may be arranged symmetrically at equal distances within the casing A, with supply and exhaust ports in the casing A for each barrel, and that by increasing the number of barrels I may secure a series 25 of explosions of comparatively small charges, and thereby the development of a continuous pressure for operating the motor, which is preferable to exploding at greater intervals larger charges.

30 The cycle of operations may be recapitulated as follows: The barrels D being stationary and the disks B and F revolving with the shaft, while the inner end of a barrel D is closed by disk F, a charge of explosive mixture is admitted to that barrel from its adjacent port J in the casing A through the channel *j* in disk B, which channel establishes communication between that particular port J and that particular barrel. Upon disk B 35 revolving further, communication between port J and the barrel is cut off, and the opening *y* in the disk B next comes opposite the outer end of the barrel. Since there is a flame-igniter mounted on the disk immediately adjacent to the opening *y*, the gases 40 tending to escape through that opening are thereby ignited and the charge is exploded just as the opening *y* passes beyond the barrel. The gases flowing from the barrel will pass 45 directly to the pressure-chamber N through an opening M in the disk F, which opening is timed to uncover the inner end of the barrel just at the time of explosion. Upon further rotation of disk B a channel *h* in the disk 50 is brought opposite the barrel D and an adjacent exhaust-port H in the casing, communication thus being established between the barrel and the exhaust-port, so that any products of combustion remaining in the barrel 55 60 which have not passed into the pressure-chamber N may escape. Before communication is established between a barrel and its exhaust-port in the casing the inner end of the barrel is closed by a solid portion of disk 65 F. This same cycle of operations of charging

a barrel, igniting the charge, admission of the gases to the pressure-chamber N, and the exhausting of any products of combustion remaining in the barrel takes place for each barrel one after another, one barrel only at 70 a time being in operation.

While I have illustrated the apparatus, Figs. 1 and 2, as provided with a shaft carrying the disks B and F, it will be evident that the disks B and F may be stationary and that 75 the barrels D may be secured to arms and carried by the shaft C with precisely the same effect as above and as illustrated in Fig. 4.

Without limiting myself to the precise construction and arrangement of parts shown, I 80 claim as my invention—

1. The combination of a casing containing an annular pressure-chamber, a turbine motor arranged within said pressure-chamber, to receive the gases therefrom and to be thereby propelled, a series of barrels arranged adjacent to the periphery of the pressure-chamber, means for supplying charges of explosive mixture to and igniting the same successively in said barrels, and means for discharging the 90 barrels successively into the pressure-chamber, substantially as described.

2. The combination of a casing containing a pressure-chamber, barrels, means for putting them into and out of communication with 95 said chamber, means for supplying an explosive mixture to and igniting the same in the barrels and for conducting the gases from successive discharges to and storing them in said chamber, and a motor arranged within and 100 communicating with said chamber, substantially as set forth.

3. The combination of a casing containing a pressure-chamber, barrels, means for putting them successively into and out of communication with said chamber, means for supplying an explosive mixture to and igniting the same in the barrels successively, and for conducting them to and storing them in said chamber, and a turbine motor arranged within 105 and communicating with said chamber, substantially as set forth.

4. The combination of a motor, a casing containing a pressure-chamber communicating with the said motor, a series of barrels 110 arranged in said casing, a rotative disk constituting the breech of said barrels and provided with inlet and outlet channels, inlet and outlet ports in the casing adjacent to each barrel, a disk F rotating in front of the barrels and provided with openings, means for rotating the disks and means for igniting charges in the barrels, substantially as set forth.

5. The combination of the casing A containing a pressure-chamber, a turbine motor communicating with said chamber, a series of barrels open at the ends and arranged in said chamber, a central shaft carrying the rotative member of the turbine, two disks B, F, 115 120 125 130

rotating opposite the ends of the barrels, channels in the disk B and ports in the casting A adjacent to the barrels, means for rotating the disks B and F, and an igniting means, and means for successively igniting the charges in the barrels, substantially as set forth.

In testimony whereof I have signed my name to this specification in the presence of two subscribing witnesses.

WILLIAM B. CUTHBERTSON.
